CONTAINER CONSTRUCTION

Henry K. Powell, Chicago, Ill., assignor to Morris
Paper Mills, Chicago, Ill., a corporation of Illi-
nois

Application December 1, 1937, Serial No. 177,437

13 Claims. (Cl. 229—5.7)

This invention pertains to containers for the packing or packaging of materials and relates particularly to closures for such containers. It is customary to package various food commodities, and other materials, in bulk packages for the purpose of shipment and sale, and for this purpose it is important that the containers have closures which are securely retained in place and which close the containers tightly. However, as in the case of various perishable food commodities which are customarily kept in cold storage, it is necessary that the closure be removable with facility in order to permit periodic inspection by health authorities, etc., during the time that the package is retained in storage and prior to the time that it is delivered to the consumer. It is likewise important that after removal on such occasions, the closure be susceptible of being replaced on the container quickly and with facility, and that it continue to function as a tight closure. Such ease of removability and replacement is likewise of advantage when the package is in the hands of the consumer, in that it facilitates the dispensing of portions of the contents from time to time.

For purposes of economy, it is desirable to employ in the packaging of various commodities containers which are made for the most part of paper board or similar material and, for economy in shipment, it is desirable that such containers be of collapsible or knockdown character, so that a large number of them may be packaged and shipped in a comparatively small cubic space.

The present invention provides a closure which meets these various requirements and which can be supplied at relatively little cost.

A general object of the invention is the provision of an improved container construction including a removable closure or cover which may be placed on and removed from the container repeatedly without involving mutilation of either, together with holding or securing means for fastening the cover on the container in such fashion that it forms a tight closure therefor, the securing means being susceptible of operation with facility to release the cover, so that it may be removed, and to again fasten it in place after it has been restored to position on the container.

Another object is the provision of such a construction which is particularly adapted to use in containers having body portions of paper board or similar material.

Yet another object is the provision of such a construction which is of simple character and of such nature that it may be supplied to the user in

a disassembled or knocked-down condition and set up or assembled by him easily.

Other and further objects of the invention will be pointed out or indicated hereinafter, or will be apparent from the following explanation or in actual use of a container embodying the invention.

For the purpose of aiding in an explanation of the invention I show in the accompanying drawing forming a part of this specification, and hereinafter describe, one form in which the invention may be embodied. It is to be understood, however, that this is presented merely for purpose of illustration and is not to be construed in any fashion for the purpose of limiting the appended claims short of the true and most comprehensive scope of the invention in the art.

In said drawing,

Fig. 1 is a perspective view of the upper portion of a container embodying the invention;

Fig. 2 is a detail in the nature of a vertical section on approximately line 2—2 of Fig. 1;

Fig. 3 is a detail in the nature of a section similar to Fig. 2 but with the fastening member in cast-off position and the cover removed;

Fig. 4 is a detail of a section similar to Fig. 3 but showing the fastening element in another position;

Fig. 5 is a side elevational view of a fastening element;

Fig. 6 is an elevational view of the inner side of such element; and

Fig. 7 is a perspective view of the same.

The nature of the invention will be most quickly ascertained from a description of the illustrative embodiment shown in the drawing. The reference numeral 10 designates the body portion of the receptacle and is here shown as of cylindrical form, it being understood, of course, that the invention may be employed in containers having bodies of other forms, such as conic or various polyhedral shapes. The body member may also be of collapsible character, but it is to be understood that the invention is not limited to use in containers of that or any other specific type.

At a short distance below its upper margin the body member is provided with an outwardly extending peripheral shoulder 11, which is most clearly illustrated in Fig. 4. This may be formed by scoring the body material at a slight distance below its upper margin and bending the upper portion 12 outwardly and downwardly into contact with the peripheral surface of the body, and securing it by an adhesive or other suitable fastening. This shoulder 11 affords one of the

elements for holding an anchor ring 14 in place on the body member. This anchor ring is a hoop-like member made of sheet metal, of size such as to embrace closely the strip 12. Its upper portion is formed as an inwardly-turned flange or channel 15 wide enough to receive and fit closely upon the upper margin of the body member, and the lower end of the anchor ring is formed with an inwardly directed lip or flange 16 positioned so as to engage under the shoulder 11. Due to the slightly flexible character of the paper board body member, this anchor ring may be applied to it by the user.

The cover comprises a hoop member 17 and a closure disk 18. The hoop member 17 preferably is formed of sheet metal and is of such size as to fit the periphery of the anchor ring 14, and preferably is slightly flared at its bottom portion, as illustrated at 17a, to facilitate the entry of the latter within it. Its upper portion is bent inwardly and downwardly to form a bead 19 which overhangs the marginal portion of the closure disk 18. The closure disk may be made of paper board, and is of such diameter as to fit snugly within the member 17 so that the inner margin of the bead 19 engages it at some distance from its margin. Accordingly, when the cover is in place on the container, the closure disk 18 seats upon the arcuate crown of the flange 15, and the inner margin of the cover hoop bead 19 engages the upper surface of the closure disk approximately over the crown of the flange 15.

As a means for securing the cover on the container, I employ, in conjunction with the anchor ring 14, a plurality of fastening elements such as the clip illustrated in Figs. 5, 6 and 7. This clip is made of resilient sheet metal with a web portion 20 which, adjacent its upper end, is bowed outward slightly as at 21, and thence curved upwardly and inwardly to form a hook portion 22, which then continues downwardly as a catch portion 24, and thence upwardly as a nose portion 25. A downwardly protruding hump or embossment 26 is formed in the hook portion between its highest part and the catch portion 24. At its lower end, the web portion 20 is continued as a laterally directed flange 27 which terminates in an upwardly and obliquely directed anchor flange 28. The straight line distance between the bottom of the detent 26 and the upper margin of the anchor flange 28 is slightly less than the distance between the crown of the channel flange 15 and the bottom of the lip 16 of the anchor ring. The width of the flange 27 is slightly greater than the width of the lip 26 plus the thickness of the closure hoop 17, and the distance between the top of the flange 27 and the under surface of the highest portion of the hook 22 is slightly greater than the total height of the anchor ring plus the thickness of the closure disk 18 plus the height of the bead 19.

A plurality of these clips are attached to the container by engaging the hook portion 22 of each over the crown of the anchor ring flange 15, then pressing downwardly on top of the hook portion 22 so as to spring the hook sufficiently to permit the anchor flange 28 to be pressed inwardly past the inner margin of the lip 16. Then when pressure on top of the hook portion 22 is released, the hook portion springs up to its original form, and moves the anchor flange 28 upwardly inside the lip 16, to a position approximately as illustrated in Fig. 4. The clip is then pressed upwardly so that the anchor flange 28

is forced in between the strip 12 and the side wall of the container body to a position approximately as illustrated in Fig. 2. The clip is then swung outwardly to the position shown in Fig. 3, which movement is accommodated by the flexibility of the wall of the body member, as illustrated in exaggerated proportion in that figure. It will be observed that in both the positions illustrated in Figs. 4 and 3 the clip is retained against falling off of the anchor ring.

A plurality of the clips are thus applied to the anchor ring at suitable intervals about its circumference. When the clips are in the outwardly swung position illustrated in Fig. 3, the cover may be applied to the anchor ring by telescoping the hoop 17 thereover, an operation which is facilitated by the inwardly sloping form of the flange 15 and the slightly flared form of the lower portion 17a of the hoop. The cover is pressed down until the closure disk 18 seats on the crown of the flange 15, and then the clips are swung upwardly and pressed inwardly so that their noses 25 are cammed over the arcuate bead 19, thus swinging the hooks upwardly until the detents 26 snap over the crown of the bead 19 and engage said bead inwardly from its crown. In such position the clip remains under some elastic stress or tension between its point of bearing on lip 16 of the anchor ring and the point of bearing of the detent 26 on the bead 19 of the cover hoop. Accordingly, this spring tension of the clips exercises a continuous force which, through the instrumentality of the bead 19, presses the closure disk 18 tightly against the crown of the anchor ring flange 15. As the actual bearing area between the arcuate flange 15 and the closure disk is very narrow, a very tight closure is effected along said line of contact.

The cover may be removed when desired by pressing the clips outwardly to disengage them from the cover hoop and then lifting the cover off of the anchor ring. After such removal, the cover may be put back on and secured in place as above described.

It will be observed that although very easily operated for opening and closing the container, this closure construction fastens the cover in place on the container very securely. It will be observed, moreover, that this is accomplished without subjecting the container body to stresses, hence giving the construction particular utility in containers having bodies made of paper board or similar material. The clamping pressure which holds the cover in place is assumed entirely by the clamping ring, cover hoop, and clips. Another feature of distinct advantage resides in the fact that the entire closure structure may be assembled with facility by the user, hence permitting the container to be shipped in knocked-down condition. In such assembly, the anchoring is first applied to the body member by inserting the upper margin of the latter within the lip 16 and thence into the channel of the flange 15, whereupon the strip 12 and its shoulder 11 are pressed outwardly over the lip 16, and then mounting the desired number of clips on the anchor ring as above described.

The construction has the further advantage that containers embodying it may be supplied to users at a cost sufficiently low to warrant the container's being discarded after a single use.

What I claim is:

1. A container construction comprising the combination with the body member, of an anchor ring secured to the body member and ex-

5 tending above the upper margin thereof, a closure seating on the top of the anchor ring, and clips having swinging connection with the anchor ring such as to retain them thereon while permitting them to be moved inwardly and outwardly relative to the body member, said clips having portions for clamping engagement with the closure to hold it down on the anchor ring.

2. In a container, the combination with the 10 body member, of an anchor ring secured to the body member and enshrouding the upper margin thereof, a closure seating on the anchor ring, and clips interengaged with the anchor ring and movable outwardly relative to the body member; 15 while attached to said ring, to positions where they clear the closure, said clips having portions for engaging over the closure and holding it under resilient pressure against the anchor ring.

3. In a container, the combination with the 20 body member, of an anchor ring encompassing the body member at its upper end, a closure seating on the anchor ring, and resilient clips hooked to the anchor ring and engaging over the closure, said clips adapted to be swung outwardly on the anchor ring, without distortion, 25 to positions clear of the closure while they remain attached to the anchor ring.

4. In a container, the combination with the 30 body member, of an anchor ring encompassing and affixed to the upper end portion of the body member, a closure seating on said anchor ring and having an upstanding bead adjacent its margin, and clips hooked at their lower ends to said anchor ring so that their upper ends may 35 be swung inwardly and outwardly relative to the closure, said clips having resilient catch portions for engagement over the upstanding bead of the closure.

5. In a container, a structure as specified in 40 claim 4 and wherein said upstanding bead is arched transversely and said clips have detent portions for engagement with said bead inwardly beyond its crown.

6. In a container, the combination of a body 45 member having an outwardly projecting shoulder adjacent its upper end, an anchor ring encompassing the body member adjacent its upper end and engaged under said shoulder, a removable cover for the body member, and clips having 50 rocking attachment at their lower ends to the anchor ring so that their upper ends may be swung inwardly and outwardly relative to the body member without distortion of the clips, said clips having resilient portions engageable over 55 portions of the cover to secure it on the body member.

7. In a container, the combination specified in 60 claim 6 and wherein the anchor ring has at its lower end an inwardly extending lip engaging under the shoulder of the body member and the clips are hooked at their lower ends to said lip.

8. In a container, in combination, a body

member of flexible material, an anchor ring encompassing the body member adjacent its upper end and holding said end in shape, a removable cover for the body member, and a plurality of clips hinged to the anchor ring for swinging movement inwardly and outwardly and having resiliently movable detents adapted to snap over portions of the cover to retain the clips in their inward position and hold the cover on the body member. 10

9. In a container, the combination specified in 15 claim 8 and wherein the cover has a portion encompassing the anchor ring and a portion seating on top of the anchor ring.

10. In a container, the combination specified in 20 claim 8 and wherein the body member has portions cooperating with the clips to restrain them in their outwardly swung position clear of the cover.

11. In a container, in combination, a body 25 member, an anchor ring encompassing and secured to the upper end thereof, an end closure member seating on the anchor ring, a hoop encompassing the end closure member and fitting telescopically over the anchor ring, said hoop having a marginal bead upstanding from the end closure member, and a plurality of clips 30 hinged on the anchor ring so as to swing inwardly and outwardly, said clips having resilient catch portions engageable over said upstanding bead to clamp the end closure on the body member.

12. In a container, the combination specified in 35 claim 11 and wherein the body member and end closure member are of paper board and the anchor ring and cover hoop and clips are of metal, and the anchor ring enshrouds the upper margin of the body member and the upstanding bead of the closure hoop overlaps the upper surface of the end closure member over the upper 40 margin of the body member.

13. In a container, in combination, a body 45 member having an outwardly jutting shoulder adjacent its upper margin, an anchor ring encompassing the upper end of the body member and having an inwardly extending lip engaging under said shoulder and an inwardly extending channel-shaped flange enshrouding the upper margin of the body member, a clip having at its lower end an upwardly extending hook engaged 50 between said lip of the anchor ring and the side of the body member, said clip having at its upper end an inwardly extending catch portion affording a detent which is spaced from the upper edge of said hook by a distance less than the height 55 of the anchor ring, and a cover adapted to seat on the anchor ring, said clip adapted to be swung on the anchor ring outwardly to a position clear of the cover and inwardly to a position wherein said detent engages over a portion of the cover. 60
